FRANKFURTER ROASTING STICK

Arthur E. May, Jr., Lake Grove, Oreg.

Application January 20, 1958, Serial No. 49,302

Term of patent 7 years

(Cl. D81—10)

Fig. 1 is an elevational view of a frankfurter roasting stick embodying my new design; and Fig. 2 is an elevational view thereof taken from the left of Fig. 1 at an angle of 90°.

I claim:

The ornamental design for a frankfurter roasting stick, substantially as shown and described.
